CARBURETER FOR INTERNAL-COMBUSTION ENGINES USING HEAVY OILS.

1,351,104.

Specification of Letters Patent. Patented Aug. 31, 1920.

Application filed December 19, 1918. Serial No. 287,525.

To all whom it may concern:

Be it known that I, FERNAND GRENIER, citizen of the Republic of France, and resident of Nantes, France, (post-office address 5 No. 101 Rue des Hauts-Pavés), have invented a new and useful Carbureter for Internal-Combustion Engines Using Heavy Oils, which improvements are fully set forth in the following specification.

10 The present invention relates to carbureters for internal combustion engines using heavy oils; and it resides in the provision of an improved carbureter of the character indicated which is so constructed 15 as to be capable of application to any standard engine, the usual gasoline carbureter being retained and used generally for starting purposes.

An embodiment of the invention is illustrated in the accompanying drawing, in which:

Figure 1 is an axial vertical sectional view of the improved carbureter;

Fig. 2 is a horizontal section;

Fig. 3 is a transverse vertical section;

Fig. 4 is a transverse section taken through the coal chamber;

Fig. 5 is a detail sectional view of the water sprayer;

Fig. 6 is a similar view of the oil sprayer and its connected float chamber;

Figs. 7 and 8 are horizontal and vertical sectional views, respectively, of the union which connects the heavy oil carbureter with the gasoline carbureter; and

Fig. 9 is a diagram showing the assemblage.

Referring more particularly to the drawing, 1 indicates, generally, the heavy oil carbureter which, as shown, comprises a substantially cylindrical metal casing 2 provided intermediate its ends with opposed ports 3 and 4 in which are fitted the ends of the two sections 5, 5' of the exhaust pipe leading from the engine, either of said ports serving as the inlet for the hot exhaust gases, and the other as the outlet therefor.

Within the interior of the casing 2 there is arranged a vaporizer 6, the side walls 6' 50 of which are connected together by spaced, horizontal partitions 6'' which are formed integral with said walls and are so disposed as to provide a tortuous passage or conduit opening at one end through a port 7 in the

top wall of the casing and having at the 55 other end an inlet funnel 8 for supplying the primary air employed in connection with the heavy oil to form the fuel. The funnel 8 is open to the atmosphere, while the port 7 receives it in one end of a delivery 60 pipe 9 which is connected at its other end with the intake manifold 10 of the engine in the manner subsequently explained. The conduit 6 terminates an appreciable distance from the front end of the casing 2, and its 65 side walls 6' are spaced from the opposite side walls of said casing, so that channels or spaces 11 are provided which inclose the sides and front end of the conduit and through which the hot exhaust gases from 70 the engine travel (see Figs. 1 and 2).

The heavy oil to be utilized as fuel is stored in a container (not shown), and is supplied therefrom through a pipe 12 (Fig. 9) to a constant-level tank or chamber 13, 75 which is attached in some suitable manner to the rear end of the casing 2 immediately adjacent the funnel 8. The tank 13 has associated with it a sprayer 14 (Figs. 1 and 6), which communicates with the inlet end of the conduit 6; the quantity of oil supplied to said conduit, as well as the quantity of air passing through the funnel, being regulated by means of an adjustable throttle 15. Hence, the oil, which is drawn into the conduit in an atomized state, will be entrained in and mixed with the air just before entering the conduit; and it is this mixture of air and atomized oil which is drawn through the conduit by the suction 85 of the engine and subjected to the heating action of the hot exhaust gases circulating through the channels 11, the action of the heat tending to expand the entrained oil so that by the time the mixture reaches the 90 outlet port 7, after having traveled forward and backward through the sections of the conduit, it will be in a substantially vaporized state.

Immediately in advance of the front end 100 of the vaporizing conduit 6, there is arranged a water vaporizer 16 (Figs. 1, 2 and 4) comprising a semi-cylindrical chamber having a charging opening at its top which is closed by a threaded cap 17, and having at its top a threaded nipple 18 providing a water inlet; the interior of the chamber being designed to contain a mass of coal

19 in the form of blocks or lumps of suitable size, held down by a grating 20. The nipple 18 fits in the cupped upper part 21 of a sprayer or atomizer 22 (Fig. 5) which is 5 equipped with an adjustable needle valve 24 and is supplied with water from a tank or reservoir (not shown) by a pipe 25 (Fig. 9). The chamber 16 is spaced from the adjacent walls of the casing 2 to enable the 10 hot exhaust gases to pass entirely around it, these spaces forming continuations of the channels 11 (Fig. 2), so that hot exhaust gases will be free to act on the wall of the chamber, heating the same and the coal therein. The upper portion of the said 15 chamber communicates by way of a passage 26 with the outlet end of the vaporizing conduit 6; from which it follows that a slight suction action will be exerted in the 20 coal chamber. The water supplied to the chamber by pipe 25 is converted into steam on coming into contact with the heated coal, as well as with the wall of the chamber; and this steam, together with any volatile products which may be driven off from the 25 coal, will be drawn out through passage 26 into the conduit 6, and will there mix with the vaporized oil and air. Probably, also, some dissociation of the steam will 30 take place, especially if the coal chamber is highly heated; and in such event there will be a resultant production of carbonic oxid, carbonic acid, free hydrogen, etc., in small quantities, all of which will pass out 35 with the steam through passage 26 for admixture with the vaporized oil and air in the conduit 6.

In any case, however, the final gaseous mixture, whatever its composition may be, 40 will escape through port 7 into pipe 9, which is not attached directly to the intake 10, but to a T-coupling 27, which is interposed between said intake and a pipe 28 which forms part of or is immediately associated with, 45 the usual gasolene carbureter 29. The latter comprises a constant-level tank or chamber 30, to which is connected a jet 31 which projects into the open lower end of pipe 28, gasolene being supplied to said tank for 50 some suitable source through a pipe 32 (Fig. 9). The branch of the T-coupling 27 to which pipe 9 is immediately connected is provided with a ported rotary valve 33 for 55 controlling the passage of the gaseous mixture therethrough from the heavy oil carbureter 1, while the other branch is provided with a butterfly valve 34 having a connection 35 with a similar valve 36 mounted in pipe 28, the arrangement being such 60 that actuation of either of said valves 34 and 36 will entail a synchronous operation of the other. Valves 37, 38 and 39 are also provided in the pipes 12, 25 and 32, respectively to control the passage of the corresponding 65 liquids therethrough. When valve 39 is

completely closed, the supply of gasolene to the carbureter 29 is shut off and said carbureter, in consequence, stops working; while carbureter 1, in like manner, can be cut out by closing either of valves 33 or 37. 70 When the gasolene carbureter 29 is in operation, and the heavy oil carbureter is cut out by closing valve 37, the secondary air supply takes place through the funnel 8, conduit 6, port 7, pipe 9, etc.; but when the carbureter 75 1 is in operation and the carbureter 29 is cut out, then the secondary air is admitted through pipe 28. Hence in either case, the secondary air is supplied through the carbureter which is at that time inactive, the 80 coupling together of the two butterfly valves 34 and 36 enabling a single adjustment to suffice for both valves.

I claim as my invention:—

1. A carbureter for heavy-oil internal 85 combustion engines, comprising a casing having inlet and outlet ports for the admission and escape of the hot exhaust gases of the engine; a tortuous vaporizing conduit in said casing around which said hot gases circulate, said conduit having an air inlet at its inlet end and having its outlet end in communication with the intake manifold of the engine, whereby a suction action is exerted in the conduit; a reservoir for containing heavy oil connected to said casing adjacent the inlet end of said conduit and having a device associated with it for spraying the oil into said conduit end to mix with the air drawn thereinto; means for regulating the admission of air through said conduit end; a chamber for containing coal located within said casing in advance of said conduit and exposed to the heating action of the hot gases circulating through said casing; and means for supplying water to the bottom of said chamber to be converted into steam by the heat thereof, said chamber being in communication at its top with the outlet end of said conduit, whereby the steam will be drawn into the conduit for admixture with the mixture of air and vaporized oil passing therethrough by the suction action exerted in said chamber. 105

2. A carbureter for heavy-oil internal 115 combustion engines, comprising a casing having inlet and outlet ports for the admission and escape of the hot exhaust gases of the engine; a tortuous vaporizing conduit in said casing around which hot gases 120 circulate, said conduit having an air inlet at its inlet end and having its outlet end in communication with the intake manifold of the engine, whereby a suction action is exerted in the conduit; a reservoir for containing heavy oil connected to said casing adjacent the inlet end of said conduit and having a device associated with it for spraying the oil into said conduit end to mix with the air drawn thereinto; means for regulat- 130

ing the admission of air through said conduit end; and means controlled by the suction action created in said conduit for drawing a current of steam into the conduit at 5 the outlet end thereof for admixture with the mixture of air and vaporized heavy oil passing through the conduit.

In testimony whereof I have signed this specification in the presence of two subscribing witnesses.

FERNAND GRENIER.
